(57) CLAIM

The ornamental design for a 35 mm camera, as shown and described.

DESCRIPTION

FIG. 1 is a perspective view of the top, front and right side of a 35 mm camera showing my new design;

FIG. 2 is a front elevational view thereof;

FIG. 3 is a top plan view thereof;

FIG. 4 is a side elevational view of the left side thereof;

FIG. 5 is a side elevational view of the right side thereof;

FIG. 6 is a rear elevational view thereof;

FIG. 7 is a bottom plan view thereof;

FIG. 8 is a view similar to FIG. 1 with the lens partially extended; and,

FIG. 9 is a view similar to FIG. 1 with the lens fully extended.
